UNITED STATES PATENT OFFICE.

ELIJAH F. SPAULDING, OF BROOKLYN, NEW YORK, ASSIGNOR TO ARTHUR ZIMTBAUM,
OF BROOKLYN, NEW YORK.

VENDING-MACHINE.

1,370,232.

Specification of Letters Patent.

Patented Mar. 1, 1921.

Application filed December 14, 1918. Serial No. 266,719.

To all whom it may concern:

Be it known that I, ELIJAH F. SPAULDING, a citizen of the United States, and resident of Brooklyn, in the county of Kings and State of New York, have invented certain new and useful Improvements in Vending-Machines, of which the following is a specification.

An object of my invention is to provide simple, cheap and efficient means for vending articles upon the insertion in the machine of suitable coins which coöperate with the articles to discharge the same.

A further object of the invention is to provide a receiver for the coins adapted to cause them to discharge the articles and arranged in such manner that the coins will be discharged from the receiver by the operation of the remaining articles in the stack thereof or a weight thereon.

Further objects and characteristics of my invention and details of construction will be more fully hereinafter set forth and then pointed out in the claims.

Reference is to be had to the accompanying drawings, wherein—

Figure 1 is a vertical section of a portion of a vending machine embodying my invention;

Fig. 2 is a view looking from the right hand side of Fig. 1, parts being omitted;

Fig. 3 is a sectional detail view illustrating the discharge of one article from a stack thereof and the discharge of a coin from its receiver;

Fig. 4 is a sectional detail view illustrating the operation of a washer catcher, parts being omitted;

Fig. 5 is a fragmentary sectional detail illustrating a coin retained by a string preventing full return of the coin receiver;

Fig. 6 is a sectional detail view illustrating means for removing deposited coins from the machine;

Figs. 7 and 8 are fragmentary sectional views illustrating in detail means for preventing clogging of the machine with a plurality of coins;

Fig. 9 is a detail side view of a coin receiver;

Fig. 10 is a plan view of Fig. 9, and

Fig. 11 is a section on the line 11—11 of Fig. 10.

Similar numerals of reference indicate corresponding parts in the several views.

At 1 is indicated a casing of a vending machine containing the magazine or chute 2 to receive stacked articles 3 to be vended. The magazine is shown provided with spaced ledges 4 at the lower part to sustain the articles 3, with the lower article opposing the opening 5 at the lower part of the magazine through which the articles may be successively discharged therefrom. A suitable weight 6 upon the articles serves to aid in causing their descent. The aforesaid parts may be constructed in any well known manner. At 7 is a plate or wall having a coin slot 8, which plate is secured to the lower front door 9 of the casing that is pivotally supported in the casing upon a bar 10. The upper door 9^a is pivotally or removably secured to the casing and retained closed by a suitable lock in any well known manner. At 7 is a plate or wall having a coin slot 8, which plate is secured to the lower front door 9 of the casing that is pivotally supported in the casing upon a bar 10. The upper door 9^a is pivotally or removably secured to the casing and retained closed by a suitable lock in any well known manner. The plate 7 bears against a stop 11 secured within the casing (Fig. 1) against which the plate 7 bears when the lower door 9 is closed, and the lower part of the upper door 9^a is shown outside of the upper portion of said plate, whereby when the upper door 9^a is locked the coin-slot plate and lower door 9 will also be locked. The lower door 9 is shown provided with a coin receptacle 12 having an opening at the upper end below the magazine to receive the coins discharged from the receiver hereinafter described, which receptacle may be secured to the lower door 9 in any suitable manner. The arrangement is such that the lower door 9 may be swung outwardly as indicated in Fig. 6, whereby the coins collected in the receptacle 12 may be removed. One or more magazines 2 may be secured within the casing side by side and a coin slot 8 is provided for each of said magazines in a well known manner. At 14 is indicated a coin receiver provided with a vertical discharging opening 15 therethrough, there being one of such openings for each coin slot located below the same to receive coins therefrom. Said opening is of greater width than the diameter of a proper coin *a*, for the machine, and the receiver is provided with a movable stop 16 which normally is retained by a spring 17 in such a position that a proper coin will rest between the adjacent edge of said stop and the opposing edge 15^a of the opening 15 of the receiver. (Fig. 10). The stop 16 is shown carried by a bar 16^a slidably mounted upon the receiver to move with 110

the stop 16 respecting the coin in the receiver. Said bar is shown provided with slots 16^b respectively receiving a screw 18 secured in the receiver 14 and the reduced end of a push rod 19 that may be secured to said receiver by means of a nut 19^a, (Fig. 10). The push rod is slideable in an opening 20 in door 9 and projects forward in position to be pushed for operating the coin receiver. The bar 16^a is shown provided with projection 21 to receive one end of the spring 17 the other end of said spring being shown secured to a projection 22 on the receiver 14, whereby the bar 16^a is normally drawn into engagement with one or both stops 18, 19. The normal position of stop 16 is thus retained spaced from stop 15^a, and said stop may be movable laterally with said bar for the discharge of the coin downwardly through the opening 15 of the receiver. When the receiver is provided with two or more coin receiving openings 15, bar 16^a may have a corresponding number of stops 16 spaced from the corresponding stop 15^a with relation to the adjacent opening 15, (Fig. 10). To guide the receiver and prevent it from tilting when operated, said receiver is shown provided with lateral projections 23 at its ends slideable upon ways 24 carried by the lower door 9. (Figs. 2 and 9). The ways 24 may project from the side walls of the receptacle 12 as a convenient means for construction. The position of receiver 14 is such that when the coin is lodged in opening 15 of the receiver and rests at its edges between the corresponding stops 15^a, 16, the upper portion of the coin will oppose the rear opening 2^a of the corresponding magazine or chute and the forward portion of the lowermost article 3 in the magazine for discharging the article therefrom when the receiver with the coin is pushed inwardly. A spring 24 connected with lower door 9 and with receiver 14, as to a projection 25 extending from said receiver, serves to restore the receiver to normal coin-receiving position when the push rod 19 is released. The forward movement of the receiver is arrested by a stop 26 secured to plate 27 in such a position that the coin *a* in the receiver will be brought to rest beneath a stack of articles, so that when the lowermost article 3 of the stack has been discharged the said stack will descend upon such coin (Fig. 3) and discharge it downwardly through the opening 15 of receiver 14 and release the coin from the stops 15^a, 16 to cause the coin to fall below into receptacle 12. The weight of the articles 3 with the weight 6 thereon will be such as to overcome the action of the spring 17 and permit the discharge from the receiver of a coin upon the articles descending thereon when the previous lowermost article has been ejected from the stack.

As the articles are ejected from the stack

they fall upon plate 27 for delivery into the passageway 28, shown between the curved rear wall 12^a of receptacle 12 and the opposing wall 29 secured in casing 1, an outlet at 30 from said passageway being provided below the door 9 for discharge of the articles, which may rest against a stop 31 at the lower edges of the casing, (Fig. 1). To prevent the insertion of an implement, such as a wire, through the opening 30 and the passageway 28, for the surreptitious extraction of articles from the corresponding magazine, I provide within said passageway one or more baffles 32, 33 on the opposite sides of the passageway. The baffle 32 is shown in the form of a plate secured to casing 1 and the baffle 33 is shown recessed or in the form of a pocket which may be secured to the side walls of the casing and extended along in front of wall 12^a of the receptacle 12. If a wire be inserted through the opening 30 it will be prevented by one or the other of said baffles from reaching the articles in the magazine, or if the wire should pass beyond the baffle 33 it would be prevented from reaching the articles in the magazine by passing along the adjacent wall of casing 1.

To prevent the machine being clogged with succeeding coins, washers and the like, I provide a rocking member 34 beneath the corresponding coin slot, which member is provided with projections 34^a, 34^b, one above the other, which may be spaced more than the diameter of a proper coin. The member 34 is pivotally supported at 35 upon a plate 36 below the coin slot. Said plate is pivotally supported within the casing to swing relatively to the magazine with the member 34, there being one such member for each coin slot. I have shown hooks 37 secured to the magazine within the casing receiving projections 38 of plate 36, whereby the latter may hang and be readily removed. A space for the passage of coins is provided between plate 36 and the magazine. A spring 39 interposed between plate 36 and the magazine serves normally to move said plate from the magazine, (Figs. 1 and 4). The lower portion of plate 36 is shown provided with a ledge 40 which is downwardly inclined and in such a position that the coins falling from the coin slot to said ledge will be caused to drop therefrom into the corresponding opening 15 of the adjacent receiver. In Fig. 2 the ledges 40 are shown oppositely inclined to direct the coins to the corresponding spaced openings 15 of the receiver from the corresponding coin slots above. The arrangement is such that projection 34^a of member 34 normally is retained across the coin passage *a* by reason of its weighted lower portion, whereby when the coin engages said projection it will tilt the member 34, causing said pro-

jection to move to one side so that when the coin is in the receiver the lower projection will be retained and the upper projection 34^b of said member will be moved in position to obstruct the passage of another coin *a* into the receiver, (Figs. 7 and 8). Such succeeding coin will be deflected by projection 34^b to pass through space 41 between receptacle 12 and door 9 to return to the operator 10 through the opening 30. When the receiver has been operated the coin will pass away from the projection 34^a allowing the member 34 to move from the position shown in Fig. 8 to the normal position shown in Fig. 7 for a succeeding coin. The arrangement 15 described prevents the accumulation of coins or tokens in the machine.

When the receiver is in normal position the plate 36 is retained in position toward 20 the magazine by means of rocker or bell-crank 42, shown pivotally supported at 43 upon a stud or projection 44 extending from the lower door 9, the upper arm of which rocker is adapted to engage plate 36, lower arm of which rocker is adapted to be 25 engaged by the projection 45 extending from the receiver, (Fig. 1). When the receiver is pushed forward the projection 45 will release rocker 42 to permit plate 36 to be pushed laterally by spring 39, and upon the return of the receiver to normal the projection 45 will operate said rocker to restore plate 36 to normal position spaced from the magazine. Upon plate 36, for 30 each coin slot, a washer catcher 46 is pivotally supported at 47, which washer catcher is provided with a projection 46^a, above the corresponding ledge 40, (Fig. 2). The washer catcher is weighted in such a manner that the projection 46^a normally extends through a hole 48 in plate 36 (Figs. 3 and 4) in position to be engaged by coins and tokens from the corresponding coin slot. When the coin engages projection 46^a 35 the latter will be moved to one side to permit passage of the coin, but if a washer *b* be inserted in the coin slot it will encounter and move projection 46^a and the latter, by reason of the weight of the washer catcher, will immediately return and enter the hole in the washer while the latter is bearing against the ledge 40, thereby preventing the washer from entering the receiver. When the receiver is next pushed inwardly, the 40 rocker 42 is released, and spring 39 will push plate 36 away from the magazine, carrying the washer catcher along and releasing the washer *b* therefrom, which will pass through passageway 41 to outlet 30 below. In the normal position of the receiver it is over an inclined wall 12^b, which may be a portion of or carried by receptacle 12, the upper end of which extends forwardly beyond the normal position of the receiver to guide the washers or other tokens

to the passageway 41 as well as the coins that may be stopped upon projection 34^b of member 34, as previously described with regard to Figs. 7 and 8. In case light weight tokens are inserted in the coin slot 70 they will be engaged by the projection 46^a of the washer catcher and will be deflected thereby to one side so as not to enter the receiver, and will pass below through the passageway 41 to the opening 30. 75

The upper edge of wall 12^b is in such a position below the receiver as to permit free passage of the coins while properly in the receiver, but in such a position as to obstruct the return of the receiver to normal position 80 in case a coin or token having a string 49 attached be inserted in the coin slot and enter the receiver, (Fig. 5). If the coin or token having such a string attached enters the receiver an article 3 may be ejected from the magazine, but sufficient length of string from the coin slot down to the receiver must be permitted to enable the receiver to advance to discharge the article, and when the stack of articles drops upon such coin or token the latter will be dislodged from between the stops 15^a, 16 of the receiver but might be retained by the string projecting partly below the receiver. In such case, when the receiver returns with said coin or token the latter will encounter the upper edge portion 12^b of wall 12 and prevent the restoration of the receiver to normal position. If the string be pulled the coin cannot be restored to proper position in the receiver because the lowermost article 3 of the stack will rest upon the coin and prevent it from being pulled upwardly, (Fig. 5). 90

To prevent the loss of coins in the machine when the stack of articles to be delivered has been exhausted, I provide a laterally extending projection 6^a from weight 6, which will oppose a coin sliding down the wall 7^a beneath coin slot 8, and will cause said coin to be displaced so that it cannot enter the receiver, but will pass outside of plate 36 and the receiver into passageway 41 to the outlet 30, (Fig. 1). Said projection 6^a may be so arranged as to oppose the coin when one or more articles remain in the machine, in cases where it is not desired to vend the last article or articles of the stack, as illustrated in Fig. 1, or said projection 6^a may oppose the plate 7^a when the last article has been delivered and the weight rests 115 upon the ledges 4. 120

A magnet 50 (Fig. 1) under plate 7^a serves to deflect magnetizable tokens to prevent them from entering the receiver.

Having thus described my invention, 125 what I claim and desire to secure by Letters Patent is:—

1. A vending machine comprising a magazine for articles and having a coin slot, a receiver for coins positioned below said slot, 130

means movably supporting said receiver for discharge of articles from the magazine, and a movable member having spaced projections between the coin slot and the receiver, 5 one of said projections being in position to be engaged by a coin in its passage to the receiver to tilt said member to present the other projection thereof as an obstruction over the receiver, a coin in the receiver 10 operating with the first named projection to retain the second named projection in the path of coins from the slot to the receiver until the receiver has moved with a coin thereon to release said member, a plate movably supported and pivotally supporting 15 said member and means coöperative between said plate and receiver to retain and release said plate.

2. A vending machine comprising a magazine for articles and having a coin slot, a coin receiver movably supported to operate relatively to said magazine, a plate movably supported and spaced from the magazine above the receiver to guide coins thereto, a 25 member movably mounted upon said plate and having projections spaced one above another, means normally retaining said member in a position with the lowermost projection thereof in the path of coins into 30 the receiver and the upper projection out of such path, whereby a coin will encounter said lowermost projection and tilt the member to move its upper projection into the space between said magazine and plate, the 35 coin in the receiver retaining said upper projection in coin obstructing position until the receiver moves the coin from said member, means movably supporting the receiver whereby a coin therein will be moved from 40 said member to permit its return to its normal position and means coöperative with the receiver and plate to retain and release said plate.

3. A vending machine comprising a magazine for articles, a coin receiver operable 45 relatively to the magazine, a plate movably supported adjacent to the magazine and spaced therefrom providing a space for the passage of coins therebetween, a washer catcher pivotally supported by said plate 50 and having a projection opposing the magazine in said space to coöperate with coins or tokens passing to the receiver to retain washers in said space, means to move the plate with the washer catcher away from 55 the magazine when the receiver is not in coin receiving position to widen the space, and means coöperative between said plate and receiver for restoring the plate to normal position when the receiver returns to coin 60 receiving position.

4. A vending machine comprising a magazine for articles, a coin receiver operable relatively to the magazine, a plate movably supported adjacent to the magazine and 65 spaced therefrom providing a space for the passage of coins therebetween, a washer catcher pivotally supported by said plate, and having a projection to enter said space to coöperate with coins or tokens passing to 70 the receiver and to retain washers in said space, means to move the plate with the washer catcher away from the magazine when the receiver is not in coin receiving position to widen said space, a member movably supported in position separate from the receiver to move the plate from the magazine and coöperative with the coin receiver to be operated thereby when the receiver returns to coin receiving position to move 75 80 the plate and washer catcher toward the magazine.

Signed at New York in the county of New York and State of New York this 13th day of December, A. D. 1918.

ELIJAH F. SPAULDING.
